WILLIAM P. GREINER AND HOWARD MORSHEAD, OF PHILADELPHIA, PENNSYLVANIA, ASSIGNEES TO THE PHILADELPHIA DRYING MACHINERY COMPANY, OF PHILADELPHIA, PENNSYLVANIA, A CORPORATION OF PENNSYLVANIA.

FORM CARRIER FOR DRYING MACHINES.

Application filed June 5, 1924, Serial No. 717,944. Renewed January 11, 1928.

This invention relates generally to drying machines and more particularly to that type embodying an enclosure through which pivotally mounted forms are intermittently 5 progressed, and means operative concurrently with successive progressions to swing individual forms in opposite directions to effect exterior presentation and re-entry relative to the enclosure.

10 An important object of this invention is to provide a simple and effective means whereby inspection of the articles to be dried during placement on the forms may be accomplished with ease.

15 Another object is the provision of a novel means, functional to prevent displacement of the drying forms relative to their supports during the operation of "stripping".

A further object is to effect the automatic 20 placement of successive forms with predetermined directional disposition preceding entry into the drying enclosure; or, in other words, the series of drying forms are consecutively progressed through the drying enclosure without reversal, irrespective of any 25 directional deflections incident to boarding inspection.

Other objects and attendant advantages 30 inhering to our invention will be herein-after referred to, or become obvious from the following description of one practical embodiment thereof, the same having been chosen from other possible forms as best 35 adapted to clearly feature its characteristics and modus operandi.

In the drawings, constituting a part hereof, like parts are distinguished by the same reference characters in all the views.

Fig. I, is a fragmentary, part-sectional, 40 plan view illustrative of the application of this invention to a hosiery drier.

Fig. II, is an enlarged side elevation of one of the form-carrying arms particularly featured by this invention.

45 Fig. III, is a part sectional elevation illustrating the manner in which the form is pivotally connected to the carrier arm with capacity for compound movement.

Fig. IV, is a top plan view of the lower 50 end of the carrier arm.

Fig. V, is a section taken as indicated by the lines V—V in Fig. II.

Fig. VI, is a similar view taken on the line VI—VI in the same figure.

Fig. VII, is an enlarged detail elevation 55 of a latching mechanism hereinafter more fully explained, and as viewed in the direction indicated by the line VII—VII on Fig. I; and,

Fig. VIII, is a fragmentary plan, of the 60 means effective to return successive forms to predetermined planal relation, prior to entering the drying enclosure.

Before entering into a detailed explanation of the present invention, and in order that its true perspective may be appreciated, attention is drawn to the fact that said invention is particularly—though not essentially—well adapted for application to drying machines comprising a cylindric enclosure 9, having an annular corridor 10, through which a series of forms 11, are adapted to be progressed by means of an intermittently moved horizontally rotatable spider, fragmentary portions of the arms whereof are characterized by the numeral 12, it not being deemed essential to fully illustrate the same; as anyone but slightly acquainted with the art will fully comprehend its structure without specific illustration and descriptive matter. Secured

70 around the periphery of the horizontally rotatable spider 12, at equal distances apart, by means of lock nuts 13, 14, are a series of king-bolts 15 functional as stationary pivots 75 for outrigger arms 16. These outrigger arms 16, are each of upwardly inclined character and somewhat cruciform cross-section to afford the necessary strength and rigidity,

80 and are each provided with an integral elongated hub portion 17, by means of which they are fulcrumed to the king-bolts 15 intermediate the head 18 thereof, and the lock nut 13. It will, of course, be readily understood that the lock nuts 13, 14 provide for 85 vertical adjustment of the outrigger arms 16, as well as affording means whereby said arms may be readily removed and replaced.

90 Integral with the hub portion 17, aforesaid, are superposed lateral lugs 19, 20, of 100 the relatively irregular configuration, best shown by Figs. VI and V, respectively. These lugs 19, 20 cooperate, with instrumentalities later on fully described; while the machine is provided with a laterally projecting framework 21, affording support for a trip device 22, fashioned with relatively stepped teeth 23, 24 whereby each successive

sive form 11 receives a half-turn, as hereafter explained in detail, so that said form re-enters the drying corridor 10, with the same planal direction it emerged therefrom.

- 5 Each outrigger arm 16, is formed at its outer and upper end with a somewhat box-like or pedestal bearing 25, functional as a swivel support for the pivotally mounted form carrier, comprehensively designated by 10 the numeral 26; and said bearing is reinforced, relative to the outrigger arm 16 by a fin 27. As best seen by Figs. II and III, the bearing 25 embraces an upwardly directed cylindric extension 28, having diametrically opposed cams or teeth 29, with which engage the reversely directed complementary cams or teeth 30 on the form carrier 26. This form carrier 26, it will be seen, comprises an upper or sleeve portion 31 with 20 a co-extensive shroud 32, the latter having laterally directed teeth 33, 34 the purpose whereof will be later on explained, while on the top face of said form carrier there is provided a cam path 35 functional as 25 a stop for engagement by a latching device, comprehensively designated by the numeral 36, and best shown in Fig. VII. The form carrier 26 is also fashioned with integral angular flanges 37, having reinforcements 30 38 which project slightly beyond the vertical edges of said flanges, as clearly indicated in Figs. II and III. Transversely of the outer vertical face of the flanges 37, there is formed a lip 39, serving as an abutment 35 for the lower edge of the form 11, which is removably attached thereto, by means of tap bolts 40, having wing nuts 41, with interposition of an angle section 42 and spring washer 43. It is noteworthy at this 40 juncture, that the pedestal bearing 25 and form carrier 26 are co-axially aligned at a slight angular inclination over from the vertical, to aid the operative when clothing the form 11 with a wet article to be dried. Furthermore, attention is drawn to the stepped relation of the horizontal portions of the angular flange 37 and angle-section 42, which affords a slight overlap between 45 said flange and angle-section elements of 50 consecutively adjoining form carrier units during progression around the annular corridor 10, as indicated at 44 in Fig. I, which closes in the bottom of said corridor and thereby prevents wasteful escape of the 55 drying medium. Swiveling connection between the bearing 25, and form carrier 26, is afforded through the instrumentality of a bolt 45, the head 46 whereof is countersunk into the upper part of the sleeve portion 31, and its lower shank portion is encircled by a buffer spring 47, abutting between the inner end of the cylindric extension 28, and a nut 48, threaded on the free end of said bolt. Locking of the nut 48, in 60 adjusted position, is effected by means of

a jack 49, and it will be readily apparent that the spring 47, is placed under just sufficient compression to permit what we conveniently term—helico-axial—movement of the form carrier 26 relative to the bearing 25, as later on set forth.

Referring to the latching device 36, which is best shown in Fig. VII, it will be seen the same comprises a pedestal 50, having a basal flange 51, by means of which it is secured— 75 by bolts 52—on the laterally projecting frame 21, hereinbefore referred to. The pedestal 50 is formed at its upper part with an integral horizontal overhang 53, and spaced apertured flanges 54, functional as 80 guides for a longitudinally slidable bolt 55 having a rectangular section extension 56, cooperative with the overhang 53, to prevent rotary motion, as will be readily understood without further explanation. The bolt 55, is under the action of a compression spring 57 and the extension 56 thereof serves as an arresting stop to prevent the form 11, from rising or lifting relative to its support, as hereafter fully explained. Further, a spring influenced hard rubber buffer 58, is appropriately fitted to the pedestal, 50, for engagement by the reinforcement 38 on the advancing form carrier end to prevent clash and reduce the impact, as will be 95 quite obvious.

Having described the aggrouped instrumentalities embodied in this invention, and assuming that the spider 12, is intermittently rotated in a counter-clockwise direction, it will be readily seen, from an examination of Fig. I more particularly, that the mass of form carriers 26, are progressed through the drying corridor 10, in relatively stationary relation. This normal, or so-termed, stationary position of the form-carriers 26 and forms 11, does not conflict with their swiveling capacity about the bearings 25 and is not to be construed otherwise than as featuring their tangential disposition during transit through said corridor. Now, assuming that a form 11, has reached the position designated *a*, ready to emerge from the drying corridor 10, it will be readily understood that the undercut part 20' of the advancing upper lateral-lug 20 encounters a pin or anti-friction roller 59, on the guide ring 59', which initiates outward swinging motion of the outrigger arm 16. This initial swing of the outrigger arm 16, projects the forward end of the lower lateral lug 19 into cooperative engagement with an upstanding anti-friction roller 60, functional to complete swinging said arm 16, and supported form 11, laterally through approximately one-hundred-eighty degrees, or into the position designated *b* for stripping in the well known way while a stop 59" is effective to prevent any back-lash intermediate transfer from the pin or anti-friction roller 59 to 130

the upstanding roller 60. Concurrent with completion of the lateral swing, thus imparted to the outrigger arm 16, the form carrier 26, will have become arrested 5 by the latching device 36 hereinbefore described; that is to say, the extension 56 is projected on to the cam path 35, whereby the form 11, is held stationary and prevented from rising during the stripping operation; while the force of the impact between the parts 38 and 50 is counteracted by the hard-rubber cushion 58, as will be easily understood by an examination of the drawings. At the same time it is observable that, 10 when the outrigger arm 16 occupies position *b*, the lateral lug 20, has been moved into close juxtaposition with a second roller 61, which assists release of the latched outrigger 16, for progression with the next succeeding 15 movement of the spider 12, to the location designated *c*. During this last referred to progressive movement, it will be apparent that the outrigger arm 16 will have swiveled from a substantially radial direction to a 20 tangential one with the cam face 62—Fig. V—cooperating with a vertical flange 63 on the guide ring 59', thereby holding said 25 arm steady.

The following intermittent planetary 30 movement of the spider 12, effects advancement of the outrigger arm 16 from location *c* to re-clothing position *d*, incident to the aforesaid cam face 62, of the lateral lug 20, moving along the flange 63, and cooperation 35 of the cam face 64 with an antifriction-roller 65. At the same time it is noticeable that the outrigger arm 16, is held relatively stationary at the position *d*, by means of a 40 spring influenced restraining device 66—Fig. I—exerting pressure against the toe portion of the cam face 62.

The subsequent progressive movement of the spider 12, moves the toe 67 of the lateral lug 19, into cooperative engagement with an antifriction roller 68, about which it 45 rides, until the tooth 69 of the lug 20 engages and rides around a further roller 70, whereby the outrigger arm 16, is returned into the drying corridor 10, as indicated at

50 *e*. Incident to the last described movements, the relatively straight side 71, of the lateral lug 19, is returned into sliding engagement with the vertical flange 63 of the guide ring 59', functional to hold the massed form carriers 26, and attached forms 11, relatively 55 stationary during progress through the drying corridor 10, as hereinbefore referred to.

As it is desirable for the "boarding" operative when reclothing the form 11, to be able 60 to inspect both sides thereof, the carrier 26 is mounted by means of the bolt 45 with capacity of helico-axial movement, as hereinbefore set forth, whereby a half-turn can be imparted under control of the cams or 65 teeth 29, 30. Now in order that the turned

form 11, may be automatically restored to proper directional disposition to re-enter the drying corridor 10, during progression from position *d* to position *e*, it will be noted that the radial teeth 33, 34 on the shroud 32, successively engage the teeth 23, 24 integral with the trip device 22 attached by bolts 72 to the laterally projecting framework 21. These teeth 23, 24, 33, 34 are designed and 70 relatively positioned to impart a reverse 75 half-turn or helico-axial movement to the form 11, thereby restoring said form to its original position, as will be readily understood by anyone in the least conversant with the art, hence further explanation is deemed 80 unnecessary.

From the foregoing description it is thought that the sequence of operations associated in the present invention will be fully understood, while its inherent advantages are self evident. However, we desire to state that the particular embodiment described is by way of example only; hence the right is accordingly reserved to make all such reasonable changes and variations, 90 as fairly lie within the scope of the subjoined claims.

Having thus described our invention, we claim:

1. In a drying machine comprising an enclosure and a rotatable conveyor, the combination of outriggers fulcrumed around said conveyor, form carriers at the free ends of said outriggers having cams defining helico-axial movement, and means whereby 95 said form carriers are normally restrained against such movement.

2. In a drying machine comprising an enclosure and an intermittently rotatable conveyor, the combination of a series of outrigger arms fulcrumed around said conveyor, a form carrier swiveled to the free end of each outrigger having cams defining helico-axial movement in opposition to 100 spring pressure, means normally preventing said movement, and means effective during progressive intervals of the conveyor, to swing successive outriggers outwardly and inwardly over a semi-circular course relative 105 to the enclosure.

3. In a drying machine comprising an enclosure and an intermittently rotatable conveyor, the combination of a series of outrigger arms fulcrumed around said conveyor, a form carrier elastically swiveled to the free end of each outrigger having cams defining helico-axial movement, means normally holding said form carrier stationary, means effective during progressive intervals 110 of the conveyor to swing successive outriggers outwardly and inwardly relative to the enclosure, and trip means adapted to automatically turn successive forms into unidirectional relation concurrent with entry 115 into the enclosure.

4. In a drying machine comprising an enclosure and an intermittently rotatable conveyor, the combination of a series of outrigger arms fulcrumed around said conveyor, a form carrier elastically swiveled to the free end of each outrigger having opposed cams defining helico-axial movement, means holding the form normally stationary, means effective during progressive intervals of the conveyor to swing successive outriggers outwardly and inwardly relative to the enclosure, trip means adapted to automatically turn successive forms into uni-directional relation concurrent with entry into the enclosure, and latching means functional to hold each form stationary during the stripping operation.

5. In a drying machine comprising an enclosure and an intermittently rotatable conveyor, the combination of a series of outrigger arms fulcrumed around said conveyor, a form carrier elastically swiveled to the free end of each outrigger having opposed cams defining helico-axial movement, means normally preventing such movement, means effective during progressive intervals of the conveyor to swing successive outriggers outwardly and inwardly relative to the enclosure, trip means adapted to automatically turn successive forms into uni-directional relation concurrent with entry into the enclosure, latching means functional to hold each form stationary during the stripping operation, and restraining means effective to prevent turning of said form while being reclothed.

6. In a drying machine comprising an enclosure and a rotatable conveyor, the combination of outrigger spring influenced form carriers fulcrumed around the conveyor, said outriggers having irregularly configured lateral lugs integral with the hubs thereof, and cooperative relatively staggered obstructions within the enclosure to effect semi-rotary motion of the outriggers.

7. In a drying machine comprising an enclosure and a rotatable conveyor, the combination of outrigger arms fulcrumed around the conveyor, form carriers elastically pivoted to the free ends of said outrigger arms, irregularly configured lateral lugs integral with the outrigger hubs, cooperative relatively staggered obstructions within the enclosure to effect semi-rotary motion of the outrigger arms in reverse directions, radially directed teeth integral with the form carriers, and a complementarily toothed device adapted to impart a half-turn to the form carriers for the purpose set forth.

8. In a drying machine comprising an enclosure and a rotatable conveyor, the combination of a form carrier having cams functional to permit partial rotation and

limited axial movement whereby the form may be manually turned for inspection, cooperative locking means normally preventing such movement, and means whereby successive form carriers are automatically restored to uni-directional disposition concurrent with entry into the enclosure.

9. In a drying machine comprising an enclosure and a rotatable planetary conveyor, the combination of pivoted outriggers each having an integral cam-ended bearing, a complementarily cam-ended form support, and means elastically swiveling said support to the bearing with capacity for axial movement.

10. In a drying machine comprising an enclosure and an intermittently rotatable planetary conveyor, the combination of pivoted outrigger arms each having an integral tooth-ended bearing, a complementarily tooth-ended form carrier, and spring influenced means swiveling connecting the form carrier to the bearing with capacity for axial movement.

11. In a drying machine comprising an enclosure and a rotatable planetary conveyor, the combination of a pivotal outrigger having an integral pedestal bearing at its free end, said bearing being provided with diametrically opposed longitudinal undulations, a form carrier having complementarily configured undulations seating over said bearing, and spring influenced means swiveling said form carrier to the bearing with capacity for rotary and axial movement.

12. In a drying machine comprising an enclosure and a rotatable planetary conveyor having outrigger arms, the combination of a pivotal form carrier embodying co-extensive tubular and shroud portions, said tubular portion having integral angular section flanges, and means whereby a form may be removably attached thereto.

13. In a drying machine comprising an enclosure and a rotatable planetary conveyor having outrigger arms, the combination of a pivotal form carrier embodying co-extensive tubular and shroud portions, said tubular portion having integral angular flanges, means whereby a form may be removably attached thereto, a cam path on the lateral portion of the angular flange, and a latching device cooperative therewith to prevent rotary and longitudinal motion to the form during the stripping operation.

14. In a drying machine comprising an enclosure and a rotatable planetary conveyor having outrigger arms, the combination of a form support embodying co-extensive tubular and shroud portions, said tubular portion having integral angular flanges, means whereby a form may be removably attached thereto, a cam path on the lateral portion of the angular flange, a latch-

ing device engagable with the cam path to prevent rotary and longitudinal motion of said form carriers during the stripping operation, radial teeth on the shroud portion of the form carrier, and a trip device within the enclosure adapted to cooperate with the aforesaid teeth whereby the forms are uniformly directed for progression through the enclosure.

10 15. In a drying machine comprising an enclosure, a rotatable planetary conveyor, and outriggers having form carriers elastically pivoted to the free ends thereof, the combination of a latching device comprising a pedestal with a spring influenced bolt adapted to engage the form carrier, whereby to prevent rotary and longitudinal movement of the form while being stripped.

16. In a drying machine comprising an enclosure, a rotatable planetary conveyor, and outriggers having form carriers elastically pivoted to the free ends thereof, the combination of a latching device comprising a pedestal with a spring influenced bolt adapted to engage the form carrier whereby to prevent rotary and longitudinal movement while the form is being stripped, and

a resilient buffer supported by the pedestal to absorb the force of impact when the outrigger arms are swung into engagement with 30 said latching device.

17. In a drying machine comprising an enclosure, a rotatable planetary conveyor, and outriggers having form carriers elastically pivoted to the free ends thereof, the 35 combination of a latching device comprising a pedestal having a spring influenced bolt adapted to engage the form carrier whereby to prevent rotary and longitudinal movement while the form is being 40 stripped, a resilient buffer supported by the pedestal effective to absorb the impact when the outrigger arms are swung into engagement with said latching device, and a spring influenced restraining means cooperative 45 with successive outriggers to prevent movement thereof while the associated form is being clothed.

In testimony whereof, we have hereunto signed our names at Philadelphia, Pennsylvania, this 3rd day of June, 1924.

WILLIAM P. GREINER.
HOWARD MORSHEAD.
